UNITED STATES PATENT OFFICE

CHARLES OPPENHEIM, OF CHICAGO, ILLINOIS

DESIGN FOR A WATCHCASE

Application filed January 4, 1933. Serial No. 46,729. Term of patent 3½ years.

To all whom it may concern:

Be it known that I, CHARLES OPPENHEIM, a citizen of the United States, residing at Chicago, in the county of Cook and State of Illinois, have invented a new, original, and ornamental Design for Watchcases, of which the following is a specification, reference being had to the accompanying drawing, forming part thereof.

The figure is a perspective view of the back of a watchcase showing my new design, the front being conventional.

I claim:

The ornamental design for a watchcase as shown and described.

CHARLES OPPENHEIM.
